CLAIM

The ornamental design for an intelligent conference device, as shown and described.

DESCRIPTION

FIG. 1 is a perspective view of an intelligent conference device showing our new design in an open state; FIG. 2 is a front view thereof in an open state; FIG. 3 is a rear view thereof in an open state; FIG. 4 is a left side view thereof in an open state; FIG. 5 is a right side view thereof in an open state; FIG. 6 is a top view thereof in an open state; FIG. 7 is a bottom view thereof in an open state; FIG. 8 is a perspective view thereof in a close state; FIG. 9 is a first side view thereof in a close state viewed from zero degree; FIG. 10 is a second side view thereof in a close state viewed from 180 degrees; FIG. 11 is a third side view thereof in a close state viewed from 45 degrees; FIG. 12 is a fourth side view thereof in a close state viewed from 315 degrees; FIG. 13 is a top view thereof in a close state; and, FIG. 14 is a bottom view thereof in a close state. The dot-dashed broken lines represent a boundary of the claimed design and form no part of the claimed design. All other dashed broken lines depict portions of the intelligent conference device that form no part of the claimed design.
